United States Patent Office

Des. 202,191
Patented Sept. 7, 1965

202,191

TELEPHONE AMPLIFIER

James F. Divietro, R.R. 3, Box 151, Elkhart, Ind.

Filed July 30, 1964, Ser. No. 81,080

Term of patent 7 years

(Cl. D26—14)

FIG. 1

FIG. 2

FIG. 3

FIG. 4

FIGURE 1 is a left side, top and front perspective view of a telephone amplifier showing my new design; FIGURE 2 is a right side elevational view;

FIGURE 3 is a top plan view; and

FIGURE 4 is a rear elevational view thereof.

The perforations in the grilles are continuous within the boundaries shown.

This application is a continuation-in-part of application Serial Number D-80,541, filed June 16, 1964, which is a continuation of abandoned application Serial Number D-73,418, filed February 4, 1963.

I claim:

The ornamental design for a telephone amplifier, substantially as shown and described.
